UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

1,342,366.

Specification of Letters Patent.

Patented June 1, 1920.

Application filed June 10, 1918. Serial No. 239,125.

To all whom it may concern:

Be it known that I, ERASTUS E. WINKLEY, a citizen of the United States, residing at Lynn, in the county of Essex and State of Massachusetts, have invented certain new and useful Improvements in Heel-Building Machines; and I do hereby declare the following to be a full, clear, and exact description of the invention, such as will enable others skilled in the art to which it appertains to make and use the same.

This invention relates to heel-building machines and is primarily designed as an improvement of the heel-building machine disclosed in Letters Patent No. 1,286,472, granted December 3, 1918, to the present applicant, although the several features of the invention are also applicable to other machines of this general class.

The machine set forth in the above-indicated patent comprises a link conveyer that is fed step-by-step through a plurality of lift assembling stations at which lifts are progressively deposited upon the conveyer in superposed relation to form heel-piles composed of any desired number of lifts. The lifts are initially disposed in graded stacks within suitable magazines and are removed one at a time therefrom and transferred to the conveyer at the several assembling stations by means of a corresponding number of pickers that are swung to and fro between the magazines and the intermittently advanced conveyer. During the movement from the magazines to the conveyer, the lifts, being transferred, are dipped into a paste pot and are subsequently deposited upon the conveyer in superposed relation to form heel-piles. The heel-piles thus formed are then carried by the conveyer to a station at which they are subjected to pressure and are nailed together.

In building heels by means of the machine set forth in the patent above referred to, the resulting heel-piles are liable to be of varying heights, for the reason that the exact thickness of the component lifts is unknown and variable. This is particularly true if some or all of the lifts are of leather, since lifts of this character differ materially in thickness. Leatherboard lifts are more apt to be of known and uniform thickness,

but even with such lifts slight variations may occur, which, if cumulative, produce a heel-pile that is either too high or too low. 55

One of the objects of the present invention is to modify and improve the construction and operation of the prior machine and to provide an automatic heel-building machine which shall be capable of making 60 heels of a substantially definite height, whereby any two heels so built may be used together to form a pair of heels of like heights.

Another object of the invention is to provide the prior machine with suitable means for determining the height of partially built heels and for controlling the subsequent operation of the machine in accordance therewith to insure the production of heels of the 65 desired final height.

More specifically, it is an object of the invention to provide a heel-building machine for building heels composed of several leather lifts of unknown and possibly varying thickness and the remaining lifts of leatherboard which are of approximately known thickness, and to incorporate therein means for measuring the heels when partially built and after the leather lifts of unknown thickness have been assembled, and for controlling the selection of certain of the leatherboard lifts which are subsequently assembled thereon in order to approximately correct for any departures of the partially 80 built heel so measured from a prescribed standard height, whereby completed heels of substantially uniform height are built.

In accordance with the preferred embodiment of the invention, one of the features 90 thereof resides in apparatus located at certain of the intermediate assembling stations of the prior machine for measuring the height of a partially built heel, and in selective means that is controlled by the measuring apparatus for causing the transferring pickers to deposit upon the incomplete heel at certain of the later assembling stations a lift that is of normal thickness or one which is relatively thick or thin, according as the 100 partially built heel that is measured is determined to be of proper height, too low or too high.

Another feature of the invention lies in

a plurality of auxiliary magazines with which certain of the last pickers may co-operate, one of said magazines containing lifts that are thinner than the normal lifts 5 in the main magazine and the other containing thicker lifts, and in a plurality of measuring devices which act upon a partially built heel at intermediate assembling stations and which respectively control the operation 10 of certain of the pickers to cause them to remove a lift from one or the other of said auxiliary magazines according as the partially built heel is too high or too low.

Other objects of the invention and features whereby they are attained will become 15 apparent from the following description of the preferred embodiment of the invention.

While, for illustrative purposes, the invention is set forth as pertaining to a heel-building machine of the type shown and described in the aforesaid patent, the invention is not restricted in this respect, as certain features thereof are applicable to heel-building machines of materially different 25 character.

Throughout the specification and claims, the terms "lifts" and "heel-lifts," unless otherwise qualified, are employed in an inclusive sense as defining any blank or layer 30 of material capable of being handled by instrumentalities of the character described, more particularly, such blanks as are useful in the formation of heel-piles from which heels are ultimately produced, irrespective 35 of the particular shape of the blank or the nature of the material of which it is composed.

The preferred embodiment of the invention is illustrated in the accompanying drawings, in which, Figure 1 is a view in end elevation, of a machine constructed in accordance with the invention; Fig. 2 is an elevation of the left-hand portion of the machine, looking from the right of Fig. 1; Fig. 40 3 is an enlarged sectional view of one of the measuring pins; Fig. 4 is a plan view of one of the double clamps which co-operates with one of the sets of main and auxiliary magazines; Fig. 5 is a plan of the left-hand portion 45 of the machine illustrated in Fig. 1, showing particularly the measuring devices in their relation to the pickers; Fig. 6 is an enlarged sectional view of one of the adjustable rollers that are associated with the last two pickers and by means of which said pickers are actuated to remove a lift from 50 the main magazine or the auxiliary magazine, in accordance with the operation of the measuring devices; Fig. 7 is an enlarged 55 view, partially in side elevation and partially in section, of the measuring device for determining whether or not the partially built heel is too high, the parts of the device being illustrated in the positions which they

occupy at the time the measuring pin is 65 first brought into engagement with the heel; Fig. 8 is a view, partially in section and partially in end elevation, the section being taken on the line 8—8 of Fig. 2, and showing particularly the measuring device for 70 determining whether or not the partially built heel is too high, the parts being in the positions which they occupy after measuring a heel that is abnormally high; Fig. 9 is an enlarged view in end elevation of one of 75 the adjustable picker rollers in co-operative engagement with the cam by which the picker is actuated; Fig. 10 is a view similar to that of Fig. 8, illustrating the measuring device for determining whether or not the 80 partially built heel is too high, the parts thereof being shown in the positions which they occupy after having measured an excessively high heel and having set the adjustable roller of one of the pickers to cause 85 it to remove a lift from one of the auxiliary magazines; Fig. 11 is a view, partially in side elevation and partially in section, of a portion of the measuring device for determining whether or not a partially built 90 heel is too low, certain parts of the device being removed for the sake of clearness; Fig. 12 is a sectional view taken on the line 12—12 of Fig. 11; Fig. 13 is a sectional view of one of the double magazine clamps shown in Fig. 95 4; Fig. 14 is a view, partially in section and partially in end elevation, the section being taken on the line 14—14 of Fig. 2, and showing particularly the structural details of one of the pickers and the relative positions of certain parts of the low-heel measuring device; and Fig. 15 is a diagrammatic view or chart representing the machine of the invention and showing particularly the relative arrangement and location of certain of its 100 essential parts.

Referring to the drawings, the heel-building machine shown comprises the following main parts which are substantially similar to the corresponding elements of the prior machine, and which include a frame 20 for supporting the various mechanisms of the machine; a plurality of main magazines 22 for containing graded stacks of lifts; a link conveyer 24 intermittently advanced through 110 a plurality of assembling stations and upon which the lifts are progressively assembled in superposed relation to form heel-piles; a paste-pot 26 into which the lifts are immersed during their transferal from the magazines to the conveyer; a plurality of swinging pickers 28 for removing single lifts from the magazines, immersing the lifts in the paste-pot and subsequently depositing them at the assembling stations upon the 115 conveyer; and a pressure and nailing device 120 designated by the general reference character 30 for subjecting the completely as-

sembled heel-piles upon the conveyer to pressure and nailing together the component lifts thereof.

The machine also comprises the following parts which have been incorporated into the earlier machine in order to accomplish the results hereinbefore stated, and which include an auxiliary magazine 32, hereinafter termed the "thick-lift" magazine, for containing lifts that are relatively thicker than the lifts contained in the main magazines; an auxiliary magazine 34, hereinafter termed the "thin-lift" magazine, for containing lifts that are thinner than those within the main magazines; a measuring device, hereinafter termed the "high-heel" measuring device and including a measuring pin 36 for determining whether or not a partially built heel is too high or too thick; a measuring device, hereinafter termed the "low-heel" measuring device, and including a measuring pin 38 for determining whether or not a partially built heel is too low or too thin, and selecting mechanisms controlled by the respective measuring devices and including adjustable rollers 40 that are associated with the last two pickers for causing said pickers to remove lifts from the main or auxiliary magazines in accordance with the height determinations of the respective measuring devices.

Referring particularly to the diagrammatic representation of the machine shown in Fig. 15, the machine comprises a row of twelve main magazines 22 for containing stacks of lifts that are graded as to size, and the link conveyer 24 upon which the heels are assembled and which is advanced step-by-step through twelve assembling stations, at each of which a lift from the corresponding magazine is deposited thereon to progressively build up a heel-pile. The lifts in the main magazines 22 are removed therefrom and deposited upon the conveyer at the twelve assembling stations by means of the twelve swinging pickers 28. Each of these pickers is adapted to occupy three successive salient positions, as shown in Fig. 8,—the first A, in which a lift is removed from the main magazine 22, the second B, in which it immerses the lift so removed into the paste-pot 26 that is located intermediate the row of magazines and the conveyer, and the third C, in which it deposits the lift upon the conveyer or upon the superposed lifts already assembled thereon. The path of movement of one of the pickers is illustrated by dash lines and arrows in Fig. 14.

Every fourth picker operates in the same timed relation, and when the first, fourth, seventh, and tenth pickers occupy their depositing positions, the second, fifth, eighth and eleventh pickers are in their paste-pot

positions, and the third, sixth, ninth and twelfth pickers are in position over the main magazines. The advance of the conveyer 24 is timed with the movements of the pickers 28 so that at each step of the conveyer four single lifts are superposed thereon at four assembling stations. Thus, a plurality of heels are progressively built at the same time and one heel is completed at the last station at each step of the conveyer.

That portion of the machine which has just been briefly outlined, constitutes a part of the prior machine and forms no direct part of the present invention except as it performs certain necessary functions in the operation of the machine.

The machine of the present invention is especially intended to build heels of a prescribed height, said heels being composed of a plurality of leather lifts—three, for example—which constitute the tread end of the heel, and a plurality of leatherboard lifts which make up the heel-seat end thereof. The particular character of the lifts is, of course, immaterial.

The first three main magazines 22, beginning at the right in Fig. 15, are filled with leather lifts of unknown and variable thickness, and the remaining main magazines are filled with leatherboard lifts of substantially uniform and known thickness. The last two main magazines 22, at the left, have auxiliary magazines 32 and 34 respectively associated therewith, the auxiliary magazine 32 adjacent the last main magazine being the thick-lift magazine, and the auxiliary magazine 34 adjacent to the next to the last main magazine being the thin-lift magazine.

Inasmuch as leather lifts are of variable and unknown thickness and leatherboard lifts are of fairly uniform and definite thickness, the section of assembled lifts which is most likely to vary in height and which includes the leather lifts, is measured after the heel is partially built. If this partially built heel is of proper height, the normal operation of the machine continues, and leatherboard lifts of substantially uniform and known thickness are removed from the main magazines 22 and assembled upon the conveyer 24 to produce a heel of the desired height. If, however, the partially built heel is found by the low heel measuring device to be too low, the last picker 28 is caused to remove a relatively thick lift from the auxiliary thick-lift magazine 32 and to deposit it upon the superposed lifts on the conveyer to approximately compensate for the discrepancy. If, on the other hand, the partially built heel is determined by the high-heel measuring device to be too high, the next to the last picker is caused to take a relatively thin lift from the thin-lift auxiliary

magazine 34 and to place it upon the superposed pile to approximately compensate for the abnormal height of the measured section of the heel. Thus, by suitably determining the height of that portion of the heel which is most likely to vary, by reason of the unknown characteristic of the leather lifts, of which it is in part composed, and by effecting an approximate compensation for any variations detected, the resulting heels produced are of a substantially uniform predetermined height.

In order to permit of the measurement of the heel section of variable height, the heels are assembled upon the conveyer with the small leather lifts at the bottom, and to facilitate such an assembly, the conveyer is provided with formers 42 into which the lifts are deposited and built up into heel-piles.

Subsequent to the progressive assembly of lifts upon the conveyer into heel-piles of predetermined heights, said piles of lifts are transferred to a nailing station in which the piles are subjected to pressure and nailed together. This portion of the machine however, constitutes a part of the prior machine and forms no part of the present invention.

Having very briefly described the operation of the machine as a whole, a more detailed consideration of its structure and mode of operation will be given. The heel-building machine, illustrated in the drawings, being in the main similar in construction and operation to that of the prior machine, only a general description of the common parts thereof is deemed necessary, reference being had to the patent for a detailed description thereof.

However, that portion of the machine by means of which the partially built heels are measured and subsequently built to the predetermined height pertains directly to the present invention and will be set forth in full.

Referring to the drawings, the frame 20 is adapted to support the various parts and mechanisms of the machine, among which are the main magazines 22 that are disposed in inclined positions in a row throughout the length of the machine. The magazines 22 are of like construction and each comprises essentially a plurality of members 46 (Fig. 8) that are suitably spaced apart to form a frame for containing a stack of lifts which rest upon a movable follower 48 to which is attached a flexible member or cord 50 that passes over a pulley 52 and supports a weight 54, by means of which the follower 48 and the stack of lifts disposed thereon are constantly urged toward the upper end of the magazine.

In order to prevent the lifts from being

discharged at the upper end of the magazine, a plurality of retaining bars 56 and 58 are disposed lengthwise of the machine, and normally are in position to be engaged by the uppermost lifts in each of the magazines. When it is desired to remove lifts from the magazines, it is necessary to withdraw the retaining bars 56 and 58, which is accomplished by means of a cam 60 (Fig. 1) upon a cam-shaft 61 and a suitable mechanism including a bell-crank lever 62 that is actuated thereby and which need not be described.

At the time that the retaining bars 56 and 58 are withdrawn to permit the removal of the uppermost lifts in the main magazines, provision must be made to prevent the upward feed of the stack of lifts, and for this purpose each main magazine is provided with a clamping device that is adapted to clamp all but the uppermost of the lifts at the upper ends of the magazines. Each of the clamping devices of the main magazines comprises relatively movable clamp jaws which are actuated into clamping position at the proper time by means of cams 70 (Fig. 1) and a cam-shaft 72 through the agency of suitable actuating mechanisms, including bell-crank levers 74. These clamping devices and actuating mechanisms are in general similar to those employed in connection with combined main and auxiliary magazines that are located in the paths of movement of the last two pickers and which will be hereinafter fully set forth.

The link conveyer 24, upon which the lifts are assembled after being transferred from the magazines 22, is supported at either end upon sprockets 76 (Fig. 1) that are suitably journaled in the machine frame 20. The conveyer comprises a plurality of formers or molds 42 (Figs. 1, 2 and 7) in which the heels are built up in upright position and which are connected together by two intervening links 80. The formers 42 and the links 80 are pivotally connected by means of rods 82 and constitute an endless link conveyer.

The upper stretch of the conveyer 24 is supported upon an inverted channel-shaped member 84 (Fig. 8) that extends lengthwise of the machine, and the conveyer is actuated in a series of steps through the several assembling stations by means of an intermittent feed-and-lock actuating mechanism 115 designated by the general reference character 86 and shown in part in Figs. 8 and 10. This actuating mechanism 86 is, or may be, similar in construction and operation to that set forth in the patent above referred to, and therefore will not be described herein.

The formers or molds 42 comprise a bot-

tom-plate 90 (Fig. 7), a breast-gage 92, and a plurality of inclined and adjustable back-gages 94 that are angularly disposed with respect to one another. Without describing the details of construction of the formers, it will be understood that by adjusting the positions of the inclined back-gages 94, the formers may be adapted to receive heels of any size and form.

10 The paste-pot 26 is suitably supported by the machine frame 20 intermediate the row of main magazines 22 and the conveyer 24 and extends longitudinally of the machine.

15 The pickers 28 hereinbefore referred to, which constitute the devices for transferring the lifts from the magazines to the conveyer 24 are illustrated particularly in Figs. 2, 5, and 14. These pickers are similar in construction and operation to those of the aforesaid patent, except that the last two pickers are slightly modified in construction in order to adapt them for the purpose of the present invention. By reason of the modified construction of the last two pickers and the operation of certain of the pickers with the measuring devices already referred to, it is deemed desirable to describe the pickers in detail in order that a clear understanding of their operation with respect to the present invention may be obtained.

Each picker comprises an arm 100 (Fig. 14) which is loosely pivoted upon a shaft 102 journaled at the top of the machine. In order to swing the picker arms about the shaft 102, each arm is provided with a lug upon which is journaled a cam-roller 40, and each cam-roller engages one of a series of similar cams 104. The cams 104 are fixed upon and rotated by a cam-shaft 106 journaled in the frame of the machine and are arranged in different angular positions on the shaft and uniformly spaced so as to cause the pickers to operate in succession and at equal intervals of time. Each picker arm 100 is integral with an arm 108, to which one end of a tension spring 110 is connected, the springs acting to maintain the cam-roller 40 in engagement with the cam 104.

Each picker arm 100 carries a slide 112 which is pivotally connected by a pin 114 near its upper end with an eccentric strap 116 that embraces an eccentric 118 fixed to the shaft 102 upon which the picker arms are journaled. This shaft rotates constantly at three times the speed of the cam-shaft 106. Its rotation has no effect upon the swinging movements of the picker arms, but the eccentric mechanism, just described, operates to raise and lower the slides 112 in the picker arms, and by the combination of this movement and of the swinging movements imparted to the arms 100 by the

picker cams 104, the pickers are caused to 65 follow the required paths of movement which are approximately indicated by the dash lines and arrows in Fig. 14.

Each picker-slide 112 carries a stem 120 having an enlarged lower end 122 which 70 slides freely in the lower end of the picker slide. The upper portion of the stem 120 is reduced in diameter and slides through an opening in the upper end of the picker slide 112. The stem is normally held in its lower-most position by means of a compression spring 124 surrounding the stem 120 and inclosed within the picker slide 112, the lower end of this slide engaging the enlarged lower end 122 of the stem. When the slide 80 is advanced, however, by means of the eccentric mechanism above described and the extremity of the picker engages a lift, the spring 124 yields and permits the stem 120 to slide upwardly within the picker 85 slide 112.

To seize the lift, the picker is provided with a plurality of curved claws 126 mounted in radial slots 128 in the lower extremity of the stem. These claws are pivotally 90 mounted and are of such form that they may be either withdrawn entirely within the slots or swung in such manner that their sharp points move downwardly and outwardly to impale a lift.

This operation of the claws is produced by means of a plunger 129 which is suitably connected to the pivoted claws. The plunger 129 slides longitudinally in the stem 120 and is provided with an enlarged upper 100 head 130. Beneath this head is a compression spring 132 which normally holds the plunger in raised position so that the claws are retracted within the stem. The plunger 129 is actuated by means of a second plunger 105 134, a compression spring 136 of greater strength than the spring 132 being interposed between the heads 137 and 130 of the two plungers to permit the necessary yielding of the lower plunger when the claws 126 have fully seated themselves in the lift. The plunger 134 slides within the reduced portion of the stem 120 and it is actuated by means of a cam lever 138 which engages the upper extremity 140 thereof. This cam 115 lever 138 is pivoted upon a bracket 142 fixed to the upper end of the stem 120 and is of bell-crank form, being provided with a depending finger 144, for a purpose to be hereinafter set forth.

The cam levers 138 that are associated with the last two pickers 28 are furthermore provided with a second depending finger 146 by means of which the pickers are actuated to remove lifts from the one 125 or the other of the auxiliary magazines 32 and 34, as will be hereinafter more fully explained. A spring 148 fixed to the bracket

142 serves as a stop to limit the counter-clockwise movement of the cam lever 138.

The operation of the pickers 28 is as follows: A plurality of cams 150 by which the cam levers 138 are actuated are all mounted upon the cam-shaft 61 that also carries the cam 60 for operating the retainers. When one of the pickers 28 is swung to the general position designated by the reference letter A in Fig. 8, the finger 144 of the corresponding cam-lever 138 becomes engaged by one of the cams 150 and a raised portion thereof then swings the lever in such a direction as to cause it to depress the plungers 134 and 129, thereby forcing the claws 126 downwardly and outwardly into the lift. This action occurs after the eccentric mechanism has brought the end of the picker stem 122 firmly into engagement with the upper surface of the uppermost lift in the corresponding magazine.

As the claws must be retained in their holding position while the picker 28 is swung inwardly and until the lift has been properly disposed upon the conveyer 24, and as these movements of the picker withdraw the cam lever 138 from engagement with its cam 150, independent means are provided for holding the plunger 134 in depressed position until the proper time for releasing the lift. To this end, the latch 156 is pivoted upon the bracket 142 in position to co-operate with a keeper 158 which is adjustably mounted upon the upper end of the plunger 134 and is beveled so as to pass freely by the latch when moving downwardly.

The operation of the latch is controlled by means connected with the picker slide 112. The slide 112 as shown in Fig. 14, is provided with a lug 160, to which the upper end of a rod 162, is adjustably fixed. The lower end of this rod is provided with a shoulder 164 adapted to engage an arm 166 projecting from the latch. Within a longitudinal opening in the rod 162 slides a rod 168 having at its lower end a head 170, also adapted to co-operate with the arm 166 on the latch. The rod 168 is normally held in its upper position by means of a compression spring 172 engaging a head 174 on the rod.

The operation of the latch mechanism is as follows: When the picker slide 112 is depressed by the eccentric mechanism in the general position A (Fig. 8) of the picker and the extremity of the picker stem engages the uppermost heel lift in the magazine 22, the spring 124 yields, as hereinbefore described, so as to permit the picker stem 120 to be arrested while the slide 112 completes its downward movement. This action results in a relative movement between the bracket 142 on which the latch 156 is pivoted and the latch-operating rod 162,

whereby the latch is released and swung into inoperative position, as will be understood. At this time, however, the claw-actuating cam 150 acts to depress the plunger 134 and throw the claws 126 into operation, and also to depress the latch-keeper 158 into position to be subsequently engaged by the hooked extremity of the latch 156. During the subsequent withdrawing movement of the picker slide 112, the claw-cam 150 continues to hold the claws in operative position while the spring 124 maintains the picker stem in engagement with the lift at the top of the stack, and the resulting relative movement of the bracket 142 and the latch controlling rods causes the head 170 of the rod 168 to engage the arm 166 and swing the latch into engagement with the keeper 158. By the continued upward movement of the slide, the picker then acts to raise the lift from the stack, and the latch acts to hold the claws in operation during this movement and during the subsequent swinging movement of the picker arm.

After the picker has withdrawn the uppermost lift from the magazine, as above described, it next moves to the general position B of Fig. 8 so as to immerse the lift in the paste-pot 26. This action is produced by the combination of the swinging movement of the arm 100 and the longitudinal movement of the slide 112, the picker acting first to swing the lift over the paste-pot and then to depress it therein. Having dipped the lift into the paste, the picker then acts to raise the lift out of the paste-pot and swing it into position C (Fig. 14) above the conveyer 24 on which the heels are assembled. This conveyer is not illustrated in Fig. 14, but one of the pickers in 105 the lift-depositing position is shown in the act of depositing a lift upon the top of a partially built heel-pile.

When the picker arm 100 has been swung to the position C, the eccentric mechanism 110 acts to depress the slide 112, thereby, through the action of the spring 124, forcing downwardly the stem 122 and the lift carried thereby, so as to cause the lift to adhere to the top of the pile of assembled lifts. The throw of the eccentric is such that the downward movement of the slide 112 causes a substantial pressure to be applied through the spring 124 to the lift being deposited. The lower end of the picker stem 120, which bears on the central portion of the lift, is the ultimate pressing agent, and through this localized pressure, the air is expelled from between the lifts and the paste is spread into a thin film.

After the pressure has been applied, the continued compression of the spring 124 causes the claws to be released from the lift, since it results in a relative movement of the parts by which the latch 156 is released 130

through the action of the rod 168, as will be understood from Fig. 14. Having deposited the lift, as just described, the picker is raised by the eccentric mechanism and is 5 then swung back to the position A, thereby completing the cycle of operation of the picker. The path of movement followed by the lower extremity of the picker is represented approximately by dash lines and 10 arrows in Fig. 14. Although Fig. 14 illustrates particularly the two last pickers, which are adapted to coöperate with the auxiliary magazines, still, the relationship of the parts is similar to that of any of the 15 other pickers which coöperate with only the main magazines 22.

For convenience in manufacture, the pickers 28 are made in groups of three, the 20 cycle of operation of one of the groups being shown in Fig. 14. In the machine illustrated, there are four of such groups of pickers, whereby a twelve-lift heel may be built, although any desired number of 25 groups may be employed in accordance with the requirements of the heel to be built. From this grouping of the pickers, it is evident that every fourth picker will occupy a similar position. Thus, if the first picker is engaging a lift in the magazine 22, the 30 fourth will be in the same position, while the second and third will be respectively in the paste-pot and in the lift depositing position above the conveyer. Thus, since every fourth picker operates similarly and 35 at the same time, it is clear that in the illustrated machine, four pickers are concurrently depositing four lifts of different sizes at separated assembling stations on the conveyer, whereby a plurality of heel-piles are 40 concurrently and progressively built, a heel being completed at the last assembling station at each step or movement of the conveyer.

The assembly of lifts in one of the formers 45 or molds 42 of the conveyer having been completed, the conveyer is advanced to a nailing station, at which a nailing device designated by the general reference numeral 30 is located, and which functions to nail together the component lifts to form a completed heel.

Having described, in greater or less detail, the construction and operation of those fundamental portions of the machine by means 55 of which heels are automatically built, which portions are substantially similar to the corresponding elements of the prior machine, the novel features of the present invention through the agency of which heels 60 of predetermined heights are built, will now be fully set forth.

According to the present invention, the auxiliary magazines 32 and 34 are disposed adjacent to and beyond the last two main 65 magazines 22 and in the path of the swing-

ing movement of the last two pickers 28. The auxiliary magazine 32 is the thick-lift magazine and contains leatherboard lifts of substantially uniform and known thickness which are somewhat thicker than the lifts 70 contained in the corresponding main magazine, while the auxiliary magazine 34 is the thin-lift magazine and accordingly contains relatively thin lifts.

Both of these auxiliary magazines are of a 75 construction similar to the main magazines, which have already been described, and differ only, in that additional retainer bars 180 and 182 are provided, and in that the clamping devices of the associated main and 80 auxiliary magazines are combined and operated by a common actuating mechanism.

The retainer bars 180 and 182 are respectively mechanically associated and actuated with the main magazine retainer bars 85 56 and 58, as shown in Fig. 1, but no specific description thereof is deemed necessary.

The clamping devices associated with the auxiliary magazines 32 and 34 are, in general, similar to the main magazine clamp- 90 ing devices and are actuated concurrently therewith. For convenience, a single member 184 (Figs. 4, 8 and 13) coöperates with the upper ends of both associated magazines and is provided with stationary clamp members 181 and 186 and movable clamp members 188 and 190. The movable clamp member 188 of the main magazine has a V-shaped notch 189 to engage the upper heel-lifts in the magazine and is provided with a 100 beveled upper edge 191 to insure that the uppermost lift is not clamped. A lateral projection or pin 193 carried by the clamp member 188 projects into an opening 194 in the stationary clamp member 186 for the 105 purpose of maintaining the movable clamp member 188 in alinement. The movable clamping member 190 is quite similar to the movable clamping member 188 and is mechanically associated therewith by a plurality of links 192 that have their respective 110 ends pivotally connected thereto.

The movable clamp member 190 is provided with a slotted lateral projection 196 which is adjustably secured to a block 198 115 adapted to slide longitudinally between guideways 200 that are suitably secured to the member 184. The slotted projection 196 is fastened to a lower flange 202 of the block 198 by means of bolts 204. These bolts project through a plurality of transverse slots in a wedge-shaped member 206 that is disposed above the projection 196 and between the movable clamp member 190 and the block 198. By laterally adjusting the position of the wedge-shaped member 206, the associated movable clamping members 188 and 190 may be varied in position to suit the 120 size of lifts being acted upon.

In order to actuate these movable clamp- 130

ing members, a toggle is provided comprising a link 208 and a short arm of a bell-crank 210, the long arm thereof carrying a roller 214 that coöperates with a suitable 5 cam 70 upon the shaft 72. This cam 70 is designed to actuate the toggle, just referred to, periodically so as to effect the clamping of the upper lifts in the associated main and auxiliary magazines at the moment that 10 the retainer bars 56, 58, 180 and 182 are withdrawn. Thus, the followers 48 and 218 upon which the respective stacks of lifts rest are prevented from being raised to force the upper lifts from the top of the 15 magazines.

The clamping devices for the respective main magazines are similar to those just described, except that only a single set of relatively movable clamp-jaws is provided 20 for each magazine, the movable jaw being actuated in a manner and by a means like those just described.

In order to render the last two pickers 28 adaptable to coöperate with the auxiliary 25 magazines 32 and 34, the claw-actuating levers 138 (Fig. 14) thereof differ slightly from the corresponding levers of the other pickers, as has already been pointed out, the difference residing in the supplemental ex- 30 tended finger 146 with which these particular levers are provided and which are adapted to be engaged by the cams 150 upon the cam shaft 61 whenever the corresponding picker 28 is swung to such an extent as to 35 remove a lift from one of the auxiliary magazines.

This extended swinging movement of the last two pickers into the position D over the auxiliary magazines, as shown in Fig. 10, is 40 effected by means of a plurality of large cams 220 that are fixed to the main cam-shaft 106 and are positioned adjacent to the main cams 104 which effect the normal operation of the pickers. These double cams 45 for the last two pickers 28 are shown clearly in Figs. 2 and 5 and in dotted lines in Fig. 6, to which reference may now be had.

As already stated, the rollers 40 that are associated with the last two pickers are ad- 50 justable in position so that they may be co-operatively engaged by either one of the main operating cams 104 or by one of the large auxiliary operating cams 220. As in- 55 dicated in Fig. 6, the roller 40 occupies such a position with respect to these cams that the swinging movement of the associated picker is produced by the large auxiliary cam 220.

The roller 40 is pivotally mounted by 60 means of a threaded bolt 222 to the end of a sleeve 224 that is slidably mounted be- 65 tween special lugs 226 and 228 that constitute parts of the picker arm 100. The sleeve 224 is provided with a fixed collar 230 that has an inclined surface 232, and disposed

intermediate said surface and the lug 228 is a bifurcated wedge member 234, the legs 236 of which are tapering in form. This wedge member 234 is provided with a hooked arm 238 that extends upwardly 70 through a notch 239 between the lugs 226 and 228, and said member is maintained in alinement by means of a key 240. A spring 242 is disposed within the hollow end of the sleeve 224 and is held in place by a removable plate 244 that is screwed to the lug 226. The spring 242 tends to force the sleeve 224 and the associated roller 40 to the right, as indicated in Fig. 6, in which position the roller may be engaged by the supplemental 80 cam 220.

The position of the roller 40 of course depends upon whether the bifurcated wedge member 234 occupies its raised or its lowered position, it being evident that if said member is forced downwardly from the position illustrated in Fig. 6, the inclined collar 230 that is fixed to the sleeve 224 is forced toward the left, whereby the roller 40 is moved in a corresponding direction 90 until it coöperates only with the main actuating cam 104.

The actuation of the bifurcated wedge member 234 is effected automatically in accordance with the height of a partially built heel, by means of the measuring and selecting devices which will hereinafter be de- 95 scribed.

These measuring devices comprise the high-heel measuring device which is located 100 at the fifth from the last or the eighth assembling station, and the low-heel measuring device which is disposed at the fourth from the last or the ninth assembling station. 105

As previously explained, it is desirable to measure the height of a partially built heel, which includes all of the leather lifts of unknown thickness, and, therefore, when such a heel upon the conveyer reaches the 110 eighth assembling station, it is acted upon by the high-heel measuring device to determine whether or not it is too high.

This measuring device comprises the slotted pin 36 which, as shown in Fig. 3, is ad- 115 justably and pivotally mounted at the end of a bell-crank 248 upon a bushing 252 that surrounds a shouldered bolt 246 and is sufficiently long to permit of pivotal movements of the pin even though the bolt 246 120 is tightened to such a degree as to clamp the pin 36 with respect thereto.

The bell-crank 248 (Fig. 7) is pivotally mounted upon a bolt 254 near the end of an arm 256 which is pivotally supported upon 125 a rod 258 that is carried in bearings 260 upon a bracket 261 that is positioned upon the frame of the machine. The arm 256 is suspended from, and raised and lowered by, a cam 262 (Figs. 7 and 8) that is fixed to 130

the main cam shaft 106 and which co-operates with a roll 264 that is carried at the upper end of a yoke 266 that is connected to an intermediate point of the arm 256 by a 5 rod 268.

The arm 256 is provided with a plurality of upwardly projecting lugs 270 and 272 that serve as bearings for a rod 274 that is 10 slideable therein in a longitudinal direction.

10 The outer end of the rod 274 is disposed adjacent the upper arm of the bell-crank 248, and the inner end thereof is pivotally connected by a pin 276 to a pawl 278 that has a pivotal connection upon a pin 280 to the 15 arm 256. The pin 276 also carries a pivotal latch 282 that is urged in a clockwise direction by means of a spring 284 that is interposed between pins carried by the pawl 278 and the latch 282. The latch 282 is provided at its outer end with a notched shoulder 286 which is adapted to engage a boss 288 on the lug 272 when the rod 274 and attached pawl 278 are forced to the right to a sufficient degree. The rod 274 and the pawl 25 278 are normally held in the position indicated in Fig. 7 by means of a spring 290 that surrounds the rod 274 between the lug 272 and a collar 292 that is fixed to said rod.

In the operation of the apparatus, the 30 measuring pin 36 is first lowered into engagement with the heel that occupies the eighth assembling station by means of the cam 262, the position of the parts being as indicated in Fig. 7. This is not the measuring 35 position, however, since the slide 112 of the picker 28, that functions in the manner already explained to deposit a lift at this station, is not yet in its full down position, the action of gravity on the arm 256 and 40 associated parts being insufficient to compress the spring 290 and actuate the rod 274 and pawl 278. As the slide 112 is actuated by the eccentric mechanism into its lowermost position, the end of said slide engages 45 the extended end 294 of the arm 256 and thereby positively actuates said arm in a downward direction. The extent of downward movement is determined by the particular longitudinal adjustment of the measuring 50 pin 36 together with the height of the partially built heel being measured.

In order to adapt the high-heel measuring device to properly function, it is necessary to initially adjust the measuring pin 36 55 with respect to its pivotal connection to the bell-crank 248, so that the rod 274 is actuated to the right sufficiently to permit the shoulder 286 of the latch 282 to drop behind the lug 288 on the bearing 272 and thus 60 latch the rod 274 and associated pawl 278, only when a heel of greater than a prescribed height is being measured.

Having adjusted the pin 36 as indicated, it is evident that if the heel, being 65 measured, is of the prescribed height, or too

low, the relative movement of the bell-crank 248 with respect to the arm 256 is insufficient to actuate the rod 274 and associated pawl 278 into their latched positions; whereas, if the heel be too high, the positive 70 downward movement of the arm 256 effects a sufficient clockwise rotation of the bell-crank 248, to actuate the rod 274 and associated pawl 278 against the action of the spring 290 into their latched position shown 75 in Fig. 8.

Advantage is taken of these two positions of the pawl 278 to selectively adjust the roller 40 of the next to the last picker 28, so that the said picker is caused to remove 80 either a lift of normal thickness from the main magazine 22 or a relatively thin lift from the auxiliary magazine 34, according as the partially built heel being measured is found to be either correct or too low, or 85 too high.

This selective action is accomplished by the aid of an upright arm 298 (Figs. 2, 5 and 7) that is pivotally mounted adjacent to the arm 256 upon the rod 258. The arm 90 298 is provided with a lug 300 against which the pawl 278 normally rests and with a lug 302 beneath which the pawl 278 is positioned when the heel being measured is found to be too high. Normally, therefore, 95 the pawl 278 occupies the position indicated in Fig. 7, and remains in this position when a heel of the proper height or a low heel is measured. Therefore, when the arm 256 is raised by the cam 262 after such a heel has 100 been measured, the pawl 278 lies in such a position that it merely moves idly upwardly between the lugs 300 and 302 without effecting the actuation of the arm 298.

If, however, the partially built heel being 105 measured is found to be too high, the pawl 278 is moved into position beneath the lug 302, as indicated in Fig. 8. Therefore, when the arm 256 is subsequently raised through the operation of the cam 262, the arm 298 is 110 also raised. The arm 298 is rigidly connected by means of a yoke 306 to an arm 308 that is also pivoted upon the shaft 258 and is located opposite to the next to the last picker 28 at the eleventh assembling station. Pivotally connected to the end of the arm 308 is an upwardly projecting rod 310 (Fig. 8) having a bifurcated upper end 312 that is adapted to engage the upper hooked extremity 238 (Fig. 6) of the wedge 115 member 234 that is associated with the next to the last picker and is adapted to adjust the operative position of the roller 40 with respect to the operating cams 104 and 220. In order to maintain a parallel motion of 120 the upright rod 310, an arm 314 is pivotally connected thereto and has a pivotal support upon a pin 316 that is carried by a bracket 261. The arm 314 is further provided with an extended stop-finger 320 that co- 125 operates

tively engages a portion of the bracket 261 for the purpose of limiting the downward movement of the rod 310 and its associated parallel-motion operating linkage already 5 described.

By reason of the construction just described, it will be understood that when the arm 298 is raised in accordance with the action of the high heel measuring device, the 10 arm 308 that is associated therewith effects the elevation of the upright rod 310. The upper bifurcated end 312 thereof which engages the hooked extremity 238 of the wedge-member 234, carried by the next to 15 the last picker, therefore raises said wedge member into the position shown in Figs. 6 and 10. By this actuation, the roll 40 associated with the next to the last picker 28 is positioned so that it may be engaged by 20 the large auxiliary cam 220 which subsequently functions to swing the picker to the position D over the auxiliary magazine 34, as shown in Fig. 10, from which a relatively thin lift is removed and later deposited at 25 the eleventh station upon the heel which has just been measured.

From the foregoing description, it is clear that if a partially built heel be measured in the eighth assembling station and found to 30 be higher than a prescribed standard, the next to the last picker 28 places a relatively thin lift upon the heel when it reaches the eleventh station, whereby the discrepancy resulting from the variations of the leather 35 lifts of unknown thickness is approximately compensated for.

During the elevation of the arm 256 and associated pawl 278, and immediately after the pawl has been brought into engagement 40 with the lug 302 of the arm 298, a pin 321 upon the latch 282 is engaged by the upper hooked end of a stationary stop 322, whereby the latch 282 is withdrawn from the lug 288. Thus, the spring-actuated rod 274 and 45 its associated pawl 278 are released. They are not, however, immediately restored to their initial positions, for the reason that the engagement of the pawl 278 with the lug 302 is sufficient to prevent their return movement until the arms 256 and 308 are subsequently lowered by the cam 262.

Having raised the rod 310 and effected the adjustment of the wedge-member 234 into its upper position, the cam 262 maintains the rod 310 as well as the arms 308 and 55 256 in their upper positions until the next to the last picker 28, the roll 40 of which has just been adjusted, again returns to its lift-depositing position. In this position 60 and before the picker has been lowered by its eccentric mechanism, the hooked end of the wedge-member 234 is located within the grasp of the bifurcated end 312 of the rod 310.

65 The cam 262 then lowers the arm 256 and

pawl 278, and by reason of the engagement of the arm 256 with a laterally projecting lug 323 on the arm 298, the latter arm, and consequently its mechanically associated arm 308 and rod 310, are also forced downwardly, during which movement the wedge-member 234 is reset to its initial lowered position. The measuring apparatus is then in condition to repeat the cycle of operation hereinbefore described. 70

If the partially built heel measured at the eighth station by the high-heel measuring device is found to be correct, or too low, the pawl 278 has an idle movement and no adjustment of the roller 40 of the next to the 75 last picker 28 is effected. Therefore, this picker operates through its usual cycle and in due course removes a lift of the usual thickness from the main magazine 22 with which it coöperates, and subsequently deposits it upon the heel. The high-heel measuring device, therefore, merely effects a 80 correction in height in case the partially built heel is found to be too high. 85

Attention is now directed to the low-heel 90 measuring device which embodies the measuring pin 38 and which is located at the ninth assembling station where it acts upon each heel as advanced to this station by the conveyer. The low-heel measuring device 95 is illustrated in Figs. 11, 12, and 14 and is essentially similar to the high-heel measuring device just described. Therefore, no detailed description of the low-heel measuring device is deemed necessary, except to 100 point out the slight differences in construction and operation that characterize it. The reference characters which designate the parts of the high-heel measuring device are also applicable to the corresponding and like 105 elements of the low-heel measuring device.

The main distinction between these devices lies in the fact that although the pawl 278 of the low-heel measuring device normally occupies the position shown in dotted 110 lines in Fig. 11, it is restrained against unrestricted upward movement by means of a lug 324 that is integral with an arm 326 which is pinned to the shaft 258. Moreover, the measuring pin 38 is initially adjusted so that if the partially built heel being measured is of the proper height or 115 too high, the pawl 278 is actuated toward the right a sufficient distance to escape the lug 324 on the arm 326, in which position it 120 is latched by the latch 282, as will be understood. Therefore, as the main arm 256 which carries the pawl 278 is raised, the pawl 278 is moved idly past the lug 324 and no actuation of the arm 326 is effected. 125 However, if the partially built heel being measured is too low, the pawl 278 is retained in its normal position beneath the lug 324, so that upon the subsequent raising of the arm 256 and associated pawl 278, the upper 130

end of said pawl engages the lug 324 and therefore raises the arm 326.

The operation of the low-heel measuring device just described is rendered effective in selectively controlling the operation of the picker 28 at the last assembling station by a linkage mechanism that is similar to that located at the eleventh assembling station and which has already been described. 10 The only essential difference lies in the fact that the arm 308 of the low-heel measuring device is pinned to the shaft 258 and therefore moves with the arm 326 which is similarly secured thereto, instead of being integrally associated with said arm through the agency of a connecting yoke such as is employed in the high-heel measuring device.

From the foregoing description, it is clear that if a partially built heel that is measured in the ninth assembling station by the low-heel measuring device is found to be of the desired height or too high, the pawl 278 is moved idly past the lug 324 of the arm 326, and therefore no adjustment of the 20 roller 40 on the last picker 28 is effected. Therefore, the last picker functions in its usual manner to remove a lift of ordinary thickness from its main magazine 22. If, on the other hand, the low-heel measuring device detects a low heel at the ninth assembling station, the pawl 278 remains in such position as to effect the actuation of the arm 326 and, therefore, of the linkage at the last assembling station, by means of 25 which the roller 40 of the last picker is adjusted, whereby the large auxiliary operating cam 220 is brought into engagement with said roller and swings the picker into position to remove a relatively thick lift 30 from the auxiliary magazine 32, and to subsequently deposit it upon the heel being built to approximately correct for the variation detected by the low-heel measuring device.

From the foregoing description, it will be understood that each partially built heel which includes the leather lifts of unknown and varying thickness is measured at two different intermediate stations. At the eighth station, it is measured to determine 45 whether it is too high, and if so, the next to the last picker is caused to remove a relatively thin lift from the auxiliary magazine 34 and deposit it upon the heel. At the ninth station, the partially built heel is 50 measured to determine whether it is too low, and in that event, the last picker is caused to remove a relatively thick lift from the auxiliary magazine 32 and to deposit it upon the heel. Thus, means is provided for measuring a partially built heel and subsequently 55 and selectively correcting for any variations detected so that a heel of approximately predetermined height is insured.

Although the invention is set forth as employing a plurality of measuring devices

and in connection with a heel building machine of a particular type, it is within the spirit and scope of the invention to utilize any means for measuring a partially built heel and to control the subsequent assembly 70 of lifts thereon in order to insure heels of a predetermined height, irrespective of the specific character of the heel-building machine employed.

Having described and illustrated the preferred embodiment of the invention, that which is claimed as new is:—

1. A heel-building machine having, in combination, a support upon which a heel-pile is built, means for superposing thereon 80 a plurality of lifts of unknown thickness, means for measuring the height of a partially built heel-pile including said lifts, and means controlled by said measuring means for subsequently superposing thereon 85 lifts of known thickness to produce a heel-pile of predetermined height.

2. A heel-building machine having, in combination, a support upon which a heel-pile is built, means for superposing thereon 90 a plurality of lifts of unknown thickness, means for measuring the height of a partially built heel-pile including said lifts, means for subsequently superposing thereon lifts of known thickness, and means dependent upon said measuring means for selecting certain of said lifts of known thickness to insure a heel-pile of predetermined 95 height.

3. A heel-building machine having, in 100 combination, a support upon which a heel-pile is built, means for superposing thereon a plurality of lifts of unknown thickness, and means acting on a partially built heel-pile including said lifts for controlling the 105 selection and subsequent assembling thereon of lifts of known thickness to insure a heel-pile of predetermined height.

4. A heel-building machine having, in 110 combination, a support upon which a heel-pile is built, means for superposing thereon a plurality of lifts of unknown thickness, means for determining the height of a partially built heel-pile including said lifts, and means controlled by said last means 115 for depositing thereon a thick, thin, or normal lift of known thickness according as said partially built heel-pile varies from or conforms to a prescribed height.

5. A heel-building machine having, in 120 combination, a series of lift magazines, a support upon which a heel-pile is built, means for removing lifts from said magazines and assembling them on said support to form a heel-pile, and means for determining the height of a partially built heel-pile and selecting a lift to be deposited thereon to produce a heel-pile of the desired 125 height.

6. A heel-building machine having, in 130

- combination, a series of lift magazines, a support on which a heel-pile is built, means for removing lifts from said magazines and assembling them on said support to form a heel-pile, and means controlling the assembly of lifts to insure a heel-pile of predetermined height.
7. A heel-building machine having, in combination, a series of lift magazines, a support on which a heel-pile is built, means for removing lifts from said magazines and assembling them on said support to form a heel-pile, and means acting upon a partially built heel-pile controlling the selection of subsequently assembled lifts to insure a heel-pile of predetermined height.
8. A heel-building machine having, in combination, a series of lift magazines, a support on which a heel-pile is built, means for removing lifts from said magazines and assembling them on said support to form a heel-pile, and means acting upon a partially built heel-pile for selecting a lift of suitable thickness to be deposited thereon to insure a heel-pile of predetermined height.
9. A heel-building machine having, in combination, a series of lift magazines, a support on which a heel-pile is built, means for removing lifts from said magazines and assembling them on said support to form a heel-pile, means acting upon a partially built heel-pile for determining its height, and means controlled by said last means for selecting a thick or thin lift to be deposited thereon according as said partially built heel-pile varies from a prescribed height.
10. A heel-building machine having, in combination, a series of lift magazines, a support on which a heel-pile is built, means for removing lifts from said magazines and assembling them on said support to form a heel-pile, plural means acting successively upon a partially built heel-pile for determining its height, and plural means respectively coöperating with said last plural means for respectively causing said assembling means to select a thick lift or a thin lift according as said partially built heel-pile varies from a prescribed height.
11. A heel-building machine having, in combination, a series of lift magazines, a support on which a heel-pile is built, means for removing lifts from said magazines and assembling them on said support in superposed relation, a plurality of means acting successively upon said superposed lifts for determining the height thereof and for respectively depositing thereon a thick lift if determined to be too low and a thin lift if determined to be too high.
12. A heel-building machine having, in combination, a series of lift magazines, a support on which a heel-pile is built, means for removing lifts from said magazines and assembling them on said support to form a partially built heel-pile, means acting upon said partially built heel-pile to determine its height, and means dependent upon said last means for selecting from said magazines and depositing upon said partially built heel-pile a thick, thin, or normal lift, according as said partially built heel-pile is less than, greater than, or conforms to a prescribed height, whereby a heel-pile of predetermined height is built.
13. A heel-building machine having, in combination, a series of lift magazines, a support on which a heel-pile is built, means for removing lifts from said magazines and assembling them on said support to form a heel-pile, means for determining the height of a partially built heel-pile, and means dependent upon said last means if said partially built heel-pile is too high for selecting a thin lift from one of said magazines and depositing it upon said pile.
14. A heel-building machine having, in combination, a series of lift magazines, a support on which a heel-pile is built, means for removing lifts from said magazines and assembling them on said support to form a partially built heel-pile, means for determining the height of said partially built heel-pile, and means dependent upon said last means if the heel-pile is too low for selecting a thick lift from one of said magazines and depositing it upon said pile.
15. A heel-building machine having, in combination, a series of main lift magazines, an auxiliary lift magazine, a support upon which a heel-pile is built, means for normally removing lifts successively from said main magazines and assembling them upon said support to form a heel-pile, and means dependent upon the height of a partially built heel-pile for causing said removing and assembling means to remove a lift from said auxiliary magazine and deposit it upon said partially built heel-pile.
16. A heel-building machine having, in combination, a series of main lift magazines, an auxiliary lift magazine, a support upon which heel-piles are built, means for normally removing lifts successively from said main magazines and assembling them upon said support to form a heel-pile, and means for causing said removing and assembling means to remove a lift from said auxiliary magazine and deposit it upon a partially built heel-pile.
17. A heel-building machine having, in combination, a series of main lift magazines, auxiliary magazines for respectively holding relatively thick and thin lifts, a support upon which heel-piles are built, means for normally removing lifts successively

- from said main magazines and assembling them upon said support to form a heel-pile, means for determining the height of a partially built heel-pile, and selective means dependent upon said last means for causing said removing and assembling means to remove a lift from one or the other of said auxiliary magazines and to deposit it upon a partially built heel-pile.
- 10 18. A heel-building machine having, in combination, a series of main lift magazines, a support upon which heel-piles are built, means for removing lifts from said magazines and assembling them upon said support to form a heel-pile, said means including a movable picker, an auxiliary magazine disposed in the path of travel of said movable picker and adjacent one of said main magazines, and means acting upon a partially built heel-pile and dependent upon the height thereof for causing said movable picker to remove a lift from said auxiliary magazine or the main magazine adjacent thereto and to deposit said lift upon a partially built heel-pile.
- 15 19. A heel-building machine, having, in combination, a series of main lift magazines, a support upon which heel-piles are built, means for removing lifts from said magazines and assembling them upon said support to form a heel-pile, said means including a plurality of movable pickers, auxiliary magazines disposed in the paths of travel of the respective movable pickers and adjacent the main magazines with which they coöperate, means for determining the height of a partially built heel-pile, and means controlled by said last means for causing said movable pickers to remove lifts from the auxiliary magazines or the main magazines and to deposit them upon a partially built heel-pile.
- 20 20. A heel-building machine having, in combination, a series of main lift magazines, a support upon which heel-piles are built, means for removing lifts from said magazines and assembling them upon said support to form a heel-pile, said means including a movable picker, an auxiliary magazine disposed in the path of travel of the movable picker and adjacent to the main magazine with which it coöperates, means for actuating said movable picker, and selective means dependent upon the height of a partially built heel-pile for causing said movable picker to remove a lift from the auxiliary magazine or the main magazine adjacent thereto.
- 25 21. A heel-building machine having, in combination, a series of magazines, some of which contain lifts of unknown thickness and some of which contain lifts of known thickness, a support upon which a heel-pile is built, means for successively removing lifts from said magazines and assembling them upon said support to form a heel pile, means for determining the height of a partially built heel-pile after the lifts of unknown thickness have been assembled, and means controlled by said last means for selecting and depositing upon a partially built heel-pile lifts of the proper known thickness to insure a heel-pile of the prescribed height.
- 30 22. A heel-building machine having, in combination, a series of lift magazines, a support upon which a heel-pile is built, means for removing lifts from said magazines and assembling them on said support to form a heel-pile, and means for measuring the height of said heel-pile during the process of building.
- 35 23. A heel-building machine having, in combination, a series of lift magazines, a support upon which a heel-pile is built, means for removing lifts from said magazines and assembling them on said support to form a heel-pile, means for measuring the height of said heel-pile during the process of building, and means responsive to said measuring means for controlling the subsequent action of said removing and assembling means during the remainder of the building process.
- 40 24. A heel-building machine having, in combination, a series of lift magazines, a support upon which a heel-pile is built, means for removing lifts from said magazines and assembling them on said support to form a heel-pile, means for measuring the height of said heel-pile during the process of building, and means responsive to said measuring means for controlling the subsequent operation of the machine.
- 45 25. A heel-building machine having, in combination, a series of lift magazines, a support upon which a heel-pile is built, means for removing lifts from said magazines and assembling them on said support to form a heel-pile, and a plurality of means acting successively upon a partially built heel-pile for determining its height at different stages of the building process.
- 50 26. A heel-building machine having, in combination, a support upon which a heel-pile is built, means for successively superposing thereon a plurality of lifts, and a plurality of means respectively and independently operating after certain successive operations of said superposing means for measuring the height of the heel-pile at different stages of the building process.
- 55 27. A heel-building machine having, in combination, a support movable intermittently through a plurality of stations, means disposed adjacent said stations for succes-

sively assembling lifts upon said support in the form of a heel-pile, one lift being assembled at each station, and means disposed at an intermediate station for measuring the height of the partially built heel-pile at said station.

28. A heel-building machine having, in combination, a support movable intermittently through a plurality of stations, means

disposed adjacent said stations for successively assembling lifts upon said support in the form of a heel-pile, one lift being assembled at each station, and a plurality of means respectively disposed at different stations for successively measuring the height of the heel-pile at different stages of the assembling process.
